Patented Apr. 25, 1922.

2 SHEETS—SHEET 2.

UNITED STATES PATENT OFFICE.

ALFRED INGRAM AND HARRY INGRAM, OF BROOKLYN, NEW YORK, ASSIGNEES TO INGRAMS INCORPORATED, OF BROOKLYN, NEW YORK, A CORPORATION OF NEW YORK.

LIQUID-DISPENSING APPARATUS.

1,414,135.

Specification of Letters Patent. Patented Apr. 25, 1922.

Application filed December 31, 1918, Serial No. 269,040. Renewed September 23, 1921. Serial No. 502,686.

To all whom it may concern:

Be it known that we, ALFRED INGRAM and HARRY INGRAM, citizens of the United States, and residents of Brooklyn, in the county of 5 Kings and State of New York, have invented certain new and useful Improvements in Liquid-Dispensing Apparatus, of which the following is a specification.

Our invention has been designed more 10 particularly as a dispenser of liquid soap for toilet purposes, and in that respect our invention resides in an attractive small receptacle, preferably of tumbler outline, having a celluloid or other pyroxylin cap and means 15 for ejecting small quantities of liquid soap from the tumbler, said means being almost wholly of celluloid or like material, so that the apparatus as a whole is inexpensive, durable, cleanly, convenient of manufacture 20 and entirely reliable in use. The invention possesses novel features of construction and arrangement, and some of these are adapted for dispensing liquids other than liquid soap, and hence in the drawings forming a 25 part of our application we illustrate a liquid soap dispensing apparatus and also an ink dispensing apparatus, one construction being a modification of certain features of the other construction and the ink dispensing apparatus being adapted for discharging ink from a large bottle into an inkstand or into a fountain pen or other receiver.

Liquid and liquid soap dispensers of various kinds have heretofore been constructed, 35 and many of them are more or less complex, expensive and uncertain in their operation, and our aim has been to provide a liquid soap dispenser of reliable character and capable of being sold at very small expense 40 and at the same time a dispenser which is light in weight and capable of use on an ordinary wash or toilet stand, it being unnecessary that the liquid soap dispenser should be more than about three and one-half inches in 45 height and about two inches in width at its top. We illustrate in the drawings a modification of our invention in which the same is adapted to an ink bottle, but primarily our invention has to do with a small, neat,

inexpensive, cleanly, reliable and efficient 50 dispenser for liquid soap.

The invention will be fully understood from the detailed description hereinafter presented, reference being had to the accompanying drawings, in which:

Fig. 1 is a vertical section through a liquid soap dispensing apparatus involving our invention, the section being taken on the dotted line 1—1 of Fig. 2;

Fig. 2 is a top view of the same; 60

Fig. 3 is a horizontal section through the same, taken on the dotted line 3—3 of Fig. 1;

Fig. 4 is a horizontal section through a portion of the same and on a larger scale, 65 taken on the dotted line 4—4 of Fig. 1;

Fig. 5 is a detached top view of a flap valve employed at the lower end of the cylinder contained within the exterior receptacle;

Fig. 6 is a vertical section corresponding 70 with Fig. 1, but illustrating the apparatus with the upper end of the cylinder closed by a stopper carried at the upper end of the piston rod;

Fig. 7 is a detached perspective view, 75 partly broken away, illustrating the application of a spring, which may be a rubber band, for normally moving the piston rod and piston to their upper position shown in Fig. 1, and

Fig. 8 is a vertical section illustrating the application of our invention to a bottle for containing ink or other liquid.

In the drawings, referring to Figs. 1 to 85 10 inclusive, 10 designates a suitable receptacle, which is preferably in the form of a small glass tumbler equipped with a closing cap 11 at its upper end and having in its base an interior recess 13 containing spaced apart ribs or lugs 14. The cap 11 will preferably be formed of pyroxylin material and have a depending annular skirt 15 confining a gasket 16. The cap or cover 11 is capable of very tightly fitting upon the tumbler or receptacle 10 and will not slip therefrom during the use of the apparatus. We illustrate the receptacle 10 as containing 90 a suitable quantity of liquid soap 17.

Within the receptacle 10 is applied a vertical cylinder or barrel 18 which is preferably of pyroxylin material and at its upper end is secured by pyroxylin cement 5 within a downwardly extending flange 19 formed around a hole at the center of the cover 11. The cylinder 18 is enlarged at its upper end, as shown, whereby a shoulder 20 becomes formed therein at a suitable distance 10 below the upper end of the cylinder, and below the shoulder 20 the cylinder is preferably provided with vent holes 21. A discharge tube 22 for the soap is connected to the cylinder 18, preferably by pyroxylin cement, and said tube 22, which is preferably of pyroxylin material, is secured near its upper end within a flange 23 extending downwardly around a hole formed in the cover 11 for said tube. The upper portion 20 of the tube 22 is bent laterally to form a discharge spout 24 extending outwardly beyond the vertical plane of the receptacle 10. The lower ends of the cylinder 18 and tube 22 are enclosed by a cap 25 of pyroxylin material cemented in place, and this cap at one edge forms a chamber 26 into which the lower end of the tube 22 opens and which is in communication with the lower end of the cylinder 18 through a port 27 30 formed in the side wall of said cylinder. The cap 25 has an opening 28 in its bottom, this opening being less in diameter than the diameter of the cylinder 18, and upon the upper surface of the bottom of the cap 25 35 is placed a disk 29, preferably of pyroxylin material, which is held in position between the upper surface of the bottom of the cap 25 and the lower edges of the cylinder 18, as shown in Fig. 1. The disk 29 is slit on the 40 line of a part of a circle, as at 30, so as to form in said disk a flap valve 31, which is connected integrally with the disk 29 by a narrow neck portion 32, which, being of flexible material, permits the valve 31 to be 45 moved upwardly from the bottom of the cap 25 and returned, at the proper time, down against said bottom and over the opening 28 therein. When the flap valve 31 is in its lower position, shown in Fig. 1, it closes 50 the opening 28 and at that time no soap may enter the cylinder 18, but when the flap valve 31 is drawn upwardly by the action of the piston hereinafter referred to, the soap may enter the cylinder 18 through the 55 opening 28 and pass thence into the chamber 26 and tube 22.

Within the cylindrical barrel 18 we locate a piston-rod 33 having on its lower end a piston or plunger composed of, by preference, a disk of felt 34 and upper and lower disks, preferably of pyroxylin material, 35, confining, under reasonable compression, said disk 34. On the upper end of the piston rod 33 is provided a head 36 for convenience in operating said rod and having

a depending portion 37 which may closely enter the upper end of the cylindrical barrel 18 and serve as a stopper for the same, as shown in Fig. 6. The rod 33 and head 36 are both preferably formed from pyroxylin or equivalent composition material. Within the cylindrical barrel 18 we provide a guide 38 through which the rod 33 may travel and which is preferably in the form of a cup of pyroxylin material closely fitting the upper 75 enlarged portion of the cylindrical barrel 18 and resting on the shoulder 20 thereof. The guide 38 and piston rod 33 are connected by a rubber or elastic band 39 acting as a spring to pull the piston-rod and its piston 80 to their upper position, shown in Fig. 1. The elastic band 39 is caught in slits 40 formed in the sides of the guide 38 and in a slit or notch 41 formed in the piston rod 33 at a suitable distance below said guide, as 85 shown in Fig. 7. When the piston rod 33 is drawn to its upper position, shown in Fig. 1, the suction action of the piston on the lower end thereof will open the flap valve 31 upwardly and draw into the lower end of the 90 cylindrical barrel 18 a definite quantity of the liquid soap 17. Thereafter when the piston rod 33 and its piston are pushed downwardly by pressure applied to the head 36, the flap-valve 31 will close and the soap contained within the lower portion of the barrel 18 and cap 25 will be forced upwardly 95 through the discharge tube 22. The rod 33 may be given several movements down and up until the requisite quantity of soap has 100 been discharged through the tube 22. Both movements of the rod 33 may be performed manually, but ordinarily the downward movement of said rod will be accomplished by manual pressure on the head 36, while 105 the upward movement of said rod may be attended to by the elastic band or spring 39. The final upward movement of the piston rod 33 and its piston draws into the discharge tube 22 any soap which may be in the discharge end or nozzle 24 of said tube, so that there will be no drops hanging from said nozzle 24, nor consequent drippings therefrom.

The cap 11, barrel 18, tube 22, guide 38, rod 115 33, head 36 and cap 25 are all preferably formed from pyroxylin material, such as celluloid, owing to the cleanly non-corrosive light-weight character of that material, and the apparatus as a whole, as shown in Figs. 120 1 and 6, due to our construction, is quite inexpensive and has proven to be of high efficiency. We employ an elastic band 39 in lieu of a metal spring, because of the non-corrosive character of the rubber and because 125 in case of breakage it may readily be renewed by anyone having the apparatus, since on the withdrawal of the piston rod 33 from the cylindrical barrel 18 it will carry the guide 38 with it, thus exposing all of the 130

parts carried with the rod 33 and permitting of the ready application of a new band 39 whenever required.

We seat the lower end of the barrel 18 and cap 25 upon the ribs 14 and within the recess 13 formed in the bottom of the receptacle 10, since this serves to steady the barrel 18 centrally within the receptacle 10 and permits of the discharge of the liquid soap until substantially all of the same has been consumed. The ribs 14 are spaced apart so that the soap may pass between the same and become pulled upwardly through the opening 28 in the bottom of the cap 25 in an efficient manner.

Our invention has been particularly designed for the dispensation of liquid soap, but may be used in other connections, and therefore in Fig. 8 we illustrate the same as applied to an ink bottle 45. In the construction shown in Fig. 8, 46 denotes the cylindrical barrel of the dispensing apparatus, 47 the discharge tube connected therewith, 48 the cap connecting the barrel 46 and tube 47 at the lower end of the instrument, 49 the chamber in said cap through which the barrel 46 and tube 47 are in communication with each other, 50 the flap valve in the lower end of the barrel 46 and corresponding exactly with the constructions shown in Figs. 1, 4 and 5, 51 the piston rod having on its lower end a piston 52 corresponding with the piston shown in Fig. 1, 53 a guide seated on a shoulder 54 of the barrel 46 and corresponding with the guide and shoulder shown in Fig. 1, and 55 a supplemental tube through which the rod 51 is adapted to have its movement and which is at its lower end fastened to the upper portion of the barrel 46, said tube 55 being employed because of the depth of the ink bottle and so as to locate the features of our invention at the bottom thereof. The bottle 45 has a bottom recess 56 and ribs corresponding exactly with the recess and ribs shown in Figs. 1 and 3. The upper end portions of the discharge tube 47 and supplemental tube 55 extend through a cork 57 closing the upper end of the bottle 45, and on the cork 57 may be applied a suitable composition cap 58. The upper end of the rod 51 is provided with a suitable knob or handle 59, and the upper end portion of the discharge tube 47 is extended laterally to form a discharge nozzle 60. The construction shown in Fig. 8 corresponds with the construction shown in Fig. 1, with the exception that by reason of the depth of the bottle 45 we have applied certain additions adapting our construction for a receptacle having the depth of an ink bottle as distinguished from that of a small tumbler, the tumbler itself being shown on an enlarged scale in Figs. 1 and 6. The operation of the apparatus shown in Fig. 8 is the same as that illustrated in Fig. 1, and hence will be fully un-

derstood without special further explanation. When the apparatus of our invention is applied to an ink bottle 45, it may be conveniently used for filling an inkstand from the bottle or for filling a fountain pen.

Our invention is not limited to the nature of the contents of the receptacle, whether soap or ink, but we more particularly intend the same to be employed as a means for dispensing liquid soap or what is sometimes termed soapy-liquid.

What we claim as our invention and desire to secure by Letters-Patent, is:

1. A dispenser of the character described comprising a receptacle adapted to contain liquid, an air-tight removable closure for the upper end thereof and means carried by said closure for effecting the discharge of the liquid in limited quantities, said means comprising a barrel member immersed in the liquid, a discharge tube extending upwardly from the lower end thereof, a cap at the lower ends of said barrel and tube flanged upwardly and connecting said ends and secured thereto and affording at one side a chamber placing said barrel member and tube in communication with each other and said cap having an inlet opening in its bottom, a valve on the said bottom to control the said opening therein, a plunger in said barrel, a plunger rod extending upwardly from said plunger and having an exposed head, and a spring normally acting to move said plunger and rod towards their upper position.

2. A dispenser of the character described comprising a receptacle adapted to contain liquid, an air tight removable closure for the upper end thereof and means carried by said closure for effecting the discharge of the liquid in limited quantities, said means comprising a barrel member immersed in the liquid, a discharge tube extending upwardly from the lower end thereof, a cap at the lower ends of said barrel and tube flanged upwardly and connecting said ends and secured thereto and affording at one side a chamber placing said barrel member and tube in communication with each other and said cap having an inlet opening in its bottom, a valve on the said bottom to control the said opening therein, a plunger in said barrel, a plunger rod extending upwardly from said plunger and having an exposed head, and a spring engaging said rod within said barrel and normally acting to move said plunger and rod towards their upper position, said chamber being directly below the lower end of said discharge tube and said barrel at the side of its lower end having a port opening into said chamber.

3. A dispenser of the character described comprising a receptacle adapted to contain liquid, an air tight removable closure for the upper end thereof and means carried by said

closure, for effecting the discharge of the liquid in limited quantities, said means comprising a barrel member immersed in the liquid, a discharge tube extending upwardly from and being in communication with the lower end of said barrel member, a cap at the lower ends of said barrel and tube flanged upwardly and connecting said ends and being secured thereto and having an inlet opening in its bottom, a disk on said bottom and held between the same and the lower end of said barrel and having formed therein and integrally therewith, a flap valve to control said opening, a plunger in said barrel, a plunger rod extending upwardly from said plunger and having an exposed head, and a spring normally acting to move said rod and plunger towards their upper position, said barrel, tube, cap and disk being of pyroxylin material.

4. A dispenser of the character described comprising a receptacle adapted to contain liquid, a closure therefor and means for effecting the discharge of the liquid in limited quantities, said means comprising a barrel member immersed in the liquid and being enlarged at its upper portion to form at the base of the enlargement a shoulder, a discharge tube extending upwardly from and being in communication with the lower end of said barrel member, a cap at the lower ends of said barrel and tube and connecting the same and having an inlet opening in its bottom, a valve on said bottom to control said opening, a plunger in said barrel, a plunger rod extending upwardly from said plunger and having an exposed head, a removable guide seated on said shoulder for said rod, and a spring within said barrel engaged with said guide and said rod and normally acting to move said rod and said plunger towards their upper position.

5. A dispenser of the character described comprising a receptacle adapted to contain liquid and having an open-top recess in its bottom, a closure for said receptacle and means for effecting the discharge of the liquid in limited quantities, said means comprising a barrel member immersed in the liquid, a discharge tube extending upwardly from and being in communication with the lower end of said barrel member, a cap at the lower ends of said barrel member and tube and connecting the same and having an inlet opening in its bottom, a valve on said bottom to control said opening, and a plunger and plunger rod in said barrel, said cap being seated in said recess at the bottom of the receptacle, and said recess being of greater diameter than said cap so as to permit the liquid to pass below said cap and enter said barrel through said inlet opening.

6. A dispenser of the character described comprising a receptacle adapted to contain liquid and having an open-top recess in its

bottom, a closure for said receptacle and means for effecting the discharge of the liquid in limited quantities, said means comprising a barrel member immersed in the liquid, a discharge tube extending upwardly from and being in communication with the lower end of said barrel member, a cap at the lower ends of said barrel member and tube and connecting the same and having an inlet opening in its bottom, a valve on said bottom to control said opening, and a plunger and plunger rod in said barrel, said cap being seated in said recess at the bottom of the receptacle and said recess having on its bottom spaced apart supporting projections for said cap, and said recess being of greater diameter than said cap so as to permit the liquid to pass below said cap and enter said barrel through said inlet opening.

7. A dispenser of the character described comprising a tumbler adapted to contain liquid, a closure cap closely fitting upon the same and having two flanged openings and means for effecting the discharge of the liquid in limited quantities, said means comprising a barrel member immersed in the liquid and secured at its upper end to the flange at one of said openings in the closure, a discharge tube extending upwardly from and being in communication with the lower end of said barrel member and at its upper portion being extended through the other of said openings and secured to the flange thereat, a cap on the lower ends of said barrel member and tube and connecting the same and having an inlet opening in its bottom, a valve on said bottom to control said opening, a plunger in said barrel, and a plunger rod extending from said plunger out through said barrel, said closure cap having a flange to pass downwardly over the upper end of said tumbler and bodily carrying the said means for effecting the discharge of the liquid.

8. A dispenser of the character described comprising a tumbler adapted to contain liquid, a closure cap closely fitting upon the same and having two flanged openings and means for effecting the discharge of the liquid in limited quantities, said means comprising a barrel member immersed in the liquid and secured at its upper end to the flange at one of said openings in the closure, a discharge tube extending upwardly from and being in communication with the lower end of said barrel member and at its upper portion being extended through the other of said openings and secured to the flange thereat, a cap on the lower ends of said barrel member and tube and connecting the same and having an inlet opening in its bottom, a valve on said bottom to control said opening, a plunger in said barrel, and a plunger rod extending from said plunger out through said barrel and having an ex-

posed head and a stopper to closely fit into the upper end of said barrel where said end is exposed directly below said cap, said closure cap having a depending skirt portion 5 to pass upon the upper end of said tumbler and bodily carrying said means for effecting the discharge of the liquid.
